3 Claims. (Cl. 53—260)

The present invention relates to a machine for feeding matches or similar rod-shaped objects into boxes having rectangular bottoms, which matches are supplied with an orientation which is transverse to the longitudinal direction of the boxes, comprising a conveying path for feeding empty boxes to a filling device and a conveying path for feeding outfilled boxes from said filling device. When filling boxes in this manner it has been found that the matches have a tendency to turn out of the intended direction which is transverse to the longitudinal direction of the box because the matches are not guided by the walls of the box in the same manner as when filling the matches in the usual way, i.e. when filling the matches orientated in parallel with the longitudinal direction of the box. The fact that the heads of the matches are all directed in the same direction is attended by the fact that the upper layers of the matches are sloping which increases the tendency of the matches to turn out of the intended position.

According to the invention filling of the boxes in the intended manner is realized by arranging a further conveying path between the conveying path feeding out filled boxes and the conveying path supplying empty boxes, said further conveying path being locked in synchronism and in proper relationship with the feed in and feed out conveying paths and designed to discharge in all the empty boxes a guide member which placed in a box comprises a number of walls orientated transversely to the longitudinal direction of the box and having their upper portions secured to a rectangular frame provided with flanges projecting out of the walls of the box, said further conveying path being designed to lift the guide members from the filled boxes and after transfer to the feed in conveying path to discharge the guide members again into empty boxes, which guide members are lifted and conveyed hanging in the flanges of the frame by means of said further conveying path. Thus a box is partitioned by the walls of a guide member into which partitions the matches are fed guided by the walls which prevent the matches being turned out of the intended position. The guide members also enable filling of the boxes in two or more steps, and accordingly it is possible to discharge two consecutive batches of matches into the boxes, which batches have the heads of the matches directed in opposite directions. After filling of the boxes the guide members are lifted from the boxes and are again fed to the empty boxes by means of the further conveying path, which may be designed in various ways within the scope of the invention. Suitably it may consist of two fixedly mounted slide bars connecting the two box conveyors and sloping down to these, which slide bars are so arranged that the side flanges of a guide member present in a filled box are enabled to engage the sloping slide bars and slide up on these when the filled box is fed out, and simultaneously an impeller finger mounted on an endless belt is arranged to engage and push up the guide member along the slide bars so that the bottom edges of the walls of the guide member are lifted above the upper edges of the box and then the guide member is transferred to the feed in conveying path and is pushed down the slide bars and placed in an empty box. One of the slide bars may also be replaced, wholly or partially, by the impeller fingers being designed to be inserted under this side of the flanges

2

of the guide members to support this side of the guide members.

The invention will now be described, by way of example, with reference to the accompanying drawing in which

FIGURE 1 is a diagrammatic plan view of the machine,
FIGURE 2 is a perspective view of an embodiment of the conveying path connecting the feed out conveying path with the feed in conveying path, and

FIGURE 3 is a sectional side elevation illustrating the transfer of the guide members to the further conveying path from the feed out conveying path.

The machine shown in the drawing is provided with a feed in conveyor consisting of an endless chain 1 supported by wheels, not shown, and the chain is provided with impeller members 2 between which boxes 3 are placed. Further there is a feed out conveyor likewise consisting of an endless chain 4 provided with impeller members 5. The feed in and feed out conveyors 1, 2 and 4, 5 are synchronized and are driven step-by-step by means of a drive motor, not shown. Above the feed in conveyor 1, 2 there is a filling device 6 by means of which a first filling of the boxes with matches is effected, and above the feed out conveyor 4, 5 there is a second filling device 7 by means of which supplemental filling of the boxes is effected. Suitably the filling devices are adapted to discharge the two portions of the matches so that the heads of the matches in the two portions are directed in opposite directions. The boxes are transferred from the feed in conveyor to the feed out conveyor by means of a transfer mechanism, not shown, in the time intervals between the fillings. A further conveyor 8 for the transfer of guide members from the feed out conveyor 4, 5 to the feed in conveyor 1, 2 is driven in synchronism with these conveyors and is shown more detailed in FIGURE 2. An endless steel band 9 is supported by two wheels 10 and 11, one of which 10 co-operates with the upper half of the band and the other 11 with the lower half of the band. The wheels are mounted on turning shafts 12 and 13 which are journaled out of the perpendicular so that the band 9 has imparted to it a suitable inclination in relation to the longitudinal directions of the conveyors 1, 2 and 4, 5. Impeller members are arranged equally spaced along the circumference of the band 9 on both sides of the band, two by two joined by means of screws extending through the band. The inside impeller members 14 are adapted to co-operate with recesses (not shown) along the circumferences of the wheels 10 and 11, and the outside impeller members or fingers 15 are adapted to co-operate with the guide members. Further there is a fixedly mounted slide bar 16 extending in parallel with the linear and the upper semi-circular portions of the band 9. The path of movement of the impeller fingers 15 and the slide bar 16 are mutually situated so that the guide members 17 are supported by the impeller fingers and the slide bar, the slide bar 16 (shown as a double dotted line in FIGURE 3) co-operating with the under-surfaces 18 of flanges 19 projecting along the longitudinal sides of the guide members. The impeller fingers 15 inserted a short distance between the ends of the guide members co-operate with the under-surface 20 of the flanges 21 projecting out of the end walls of the guide members the central portions of which flanges are supported by the upper surfaces of the impeller members 2 and 5 when the guide members are advanced on the conveyors 1, 2 and 4, 5.

FIGURE 3 illustrates the lifting operation of a guide member 17 from a box 3. The guide member consists of an open frame formed by the two longitudinal flanges 19 and the two transverse flanges 21 which latter have undercut ends and are joined with the end walls 22 of the guide members. The partition walls 23 are secured to the in-

sides of the flanges 19. When the boxes are advanced in the direction indicated by an arrow the leading edge of one of the flanges 19 engages the slide bar 16 at the point P at the same time as an impeller finger 15 inserted between the guide members and moving parallel with the slide bar 16 engages the under-surface 20 of the front flange 21. In the position shown in FIGURE 3 the front portion of the guide member has been lifted a short distance whereas the rear portion is still supported by the upper surface of the impeller member 5.

At a further advance of the boxes the guide member 17 is entirely lifted from the box 3 the guide member being advanced in synchronism with the box along a straight portion of the transfer conveyor 8 located straight above the feed out conveyor 4, 5. The guide member 17 is then transferred along the semicircular portion of the conveying path to a straight portion of the path above the feed in conveyor 1, 2, where the guide member is fed down in an empty box in a manner analogous to that described above in connection with the lifting of the guide member.

The invention is not limited to the embodiment described above, but numerous modifications may be made in the construction. The feed in and feed out conveyors may, for example, be situated in line with each other and consist of a single endless belt in which case the guide members after filling of the boxes are to be fed back from the feed out path to the feed in path. Further numerous changes may be made in the construction of the conveyors and the impeller members.

What I claim is:

1. A machine for feeding matches or similar rod-shaped objects into boxes having rectangular bottoms transversely to the longitudinal direction of said boxes, comprising a first conveyor for feeding empty boxes to a box filling device, a second conveyor for feeding filled boxes from said filling device, a third conveyor arranged between said first and second conveyors, said third conveyor being locked in synchronism and in proper relationship with said first and second conveyors to discharge in all said empty boxes, a guide member which when placed in a box comprises a number of walls orientated transversely to the longitudinal direction of the box and having their upper portions secured to a rectangular frame provided with flanges projecting out of the walls of the box, means upon said third conveyor for lifting a guide member by said flanges from a filled box, conveying it to said first conveyor and discharging it into an empty box, said third

4 conveyor comprising an endless belt having impeller fingers to be inserted between said guide members and to engage said flanges on one side of said guide members and a fixedly mounted slide bar cooperating with said flanges on the other side of said guide members.

5 2. A machine as claimed in claim 1 wherein said endless belt comprises a steel band, two wheels having recesses supporting said band along the peripheries thereof, impeller members mounted two by two on both sides of said band and mutually joined with each other, said impeller members on the outside of said band cooperating with the guide members and those on the inside of said band cooperating with said recesses of the two wheels.

10 3. A machine for feeding matches or similar rod-shaped objects into boxes having rectangular bottoms transversely to the longitudinal direction of said boxes, comprising a first conveyor for feeding empty boxes to a box filling device, a second conveyor for feeding filled boxes from said filling device, a third conveyor arranged between said first and second conveyors, said third conveyor being locked in synchronism and in proper relationship with said first and second conveyors to discharge in all said empty boxes, a guide member which when placed in a box comprises a number of walls orientated transversely to the longitudinal direction of the box and having their upper portions secured to a rectangular frame provided with flanges projecting out of the walls of the box, means upon said third conveyor for lifting a guide member by said flanges from a filled box, conveying it to said first conveyor and discharging it into an empty box, said first and second conveyors being located beside each other and having opposed feeding directions, said third conveyor being located in an inclined plane and provided with two linear portions above the paths of the filled and empty boxes, respectively, connected by an upper semicircular portion, the angle of inclination and the length of said linear portions being dimensioned to transfer said guide members from said second conveyor to said third conveyor and from thence to said first conveyor.
